(57) **CLAIM**
I claim the ornamental design for a skin massager, as shown and described.

DESCRIPTION

FIG. 1 is a lower front right perspective view of a first embodiment of the skin massager.

FIG. 2 is a front view of the first embodiment of the skin massager.

FIG. 3 is a rear view of the first embodiment of the skin massager.

FIG. 4 is a left side view of the first embodiment of the skin massager.

FIG. 5 is a right side view of the first embodiment of the skin massager.

FIG. 6 is a top view of the first embodiment of the skin massager.

FIG. 7 is a bottom view of the first embodiment of the skin massager.

FIG. 8 is a lower front right perspective view of a second embodiment of the skin massager.

FIG. 9 is a front view of the second embodiment of the skin massager.

FIG. 10 is a rear view of the second embodiment of the skin massager.

FIG. 11 is a left side view of the second embodiment of the skin massager.

FIG. 12 is a right side view of the second embodiment of the skin massager.

FIG. 13 is a top view of the second embodiment of the skin massager; and,

FIG. 14 is a bottom view of the second embodiment of the skin massager.

The broken lines are directed to environment and are for illustrative purposes only; the broken lines form no part of the claimed design.

It is certified that error appears in the above-identified patent and that said Letters Patent is hereby corrected as shown below:

In the Title:

(54) replace "Skin Massager" with --Skin Cleanser--.

In the Claim:

(57) replace "skin massager" with --skin cleanser--.

In the Description:

Line 2, replace "skin massager" with --skin cleanser--.
Lines 3-4, replace "skin massager" with --skin cleanser--.
Lines 5-6, replace "skin massager" with --skin cleanser--.
Lines 7-8, replace "skin massager" with --skin cleanser--.
Lines 9-10, replace "skin massager" with --skin cleanser--.
Lines 11-12, replace "skin massager" with --skin cleanser--.
Lines 13-14, replace "skin massager" with --skin cleanser--.
Line 16, replace "skin massager" with --skin cleanser--.
Lines 17-18, replace "skin massager" with --skin cleanser--.
Lines 19-20, replace "skin massager" with --skin cleanser--.
Line 22, replace "skin massager" with --skin cleanser--.
Line 24, replace "skin massager" with --skin cleanser--.
Lines 25-26, replace "skin massager" with --skin cleanser--.
Line 28, replace "skin massager" with --skin cleanser--.
